(57) **CLAIM**

The ornamental design for a surgical handpiece, as shown and described.

DESCRIPTION

FIG. 1 is a side perspective view of a surgical handpiece showing our new design;

FIG. 2 is a top plan view thereof;

FIG. 3 is a front elevation view thereof;

FIG. 4 is a right side elevation view thereof; the left side being a mirror image.

FIG. 5 is a rear elevation thereof; and

FIG. 6 is a bottom elevation view thereof;

FIG. 7 is a top plan view of a second embodiment of a surgical handpiece showing our new design;

FIG. 8 is a front elevation view thereof;

FIG. 9 is a right side elevation view thereof; the left side being a mirror image.

FIG. 10 is a rear elevation thereof; and,

FIG. 11 is a bottom elevation view thereof.
